US00D533573S

(12) **United States Design Patent** (10) **Patent No.:** **US D533,573 S**
Barber et al. (45) **Date of Patent:** **** Dec. 12, 2006**

(54) **MONOCULAR**

(75) Inventors: **Ross F. Barber**, Pembroke, NH (US);
Ronald W. Ciccone, Jr., Bedford, NH (US)

(73) Assignee: **Insight Technology, Inc.**, Londonderry, NH (US)

(**) Term: **14 Years**

(21) Appl. No.: **29/240,816**

(22) Filed: **Oct. 19, 2005**

(51) **LOC (8) Cl. 16-99**

(52) **U.S. Cl. D16/130; D16/132**

(58) **Field of Classification Search** .... D16/130, D16/132, 133, 136; 359/418, 353, 350, 399, 359/809, 819, 407, 409; 2/6.1, 422, 426; 250/214 VT, 216; 313/524, 532

See application file for complete search history.

Primary Examiner—Paula A. Greene

(57) **CLAIM**

The original design for a monocular, as shown and described.

DESCRIPTION

FIG. 1 is a perspective view of a monocular of the present invention;

FIG. 2 is a front view of the monocular of FIG. 1;

FIG. 3 is a rear view of the monocular of FIG. 1;

FIG. 4 is a right side view of the monocular of FIG. 1;

FIG. 5 is a left side view of the monocular of FIG. 1;

FIG. 6 is a top view of the monocular of FIG. 1; and,

FIG. 7 is a bottom view of the monocular of FIG. 1.

1 Claim, 4 Drawing Sheets
